WALL LAMP

Robert D. Smith, Glen Ellyn, Ill.

Application July 6, 1950, Serial No. 10,972

Term of patent 14 years

(Cl. D48—4)

To all whom it may concern:

Be it known, that I, Robert D. Smith, a citizen of the United States, residing at Glen Ellyn, in the county of Du Page and State of Illinois, have invented a new, original, and ornamental Design for Wall Lamp, of which the following is a specification, reference being had to the accompanying drawing, forming a part hereof, in which:

Fig. 2 is a side elevational view of the same.

The dominant features of my design reside in those portions shown in full lines in the drawings.

I claim:

The ornamental design for a wall lamp, substantially as shown and described.

ROBERT D. SMITH.
